UNITED STATES PATENT OFFICE

133,557

DESIGN FOR A WRENCH

Roy Hunter Dickenson, Kingsport, Tenn.

Application March 11, 1942, Serial No. 106,147

Term of patent 14 years

To all whom it may concern:

Be it known that I, Roy Hunter Dickenson, a citizen of the United States, residing at Kingsport, in the county of Sullivan and State of Tennessee, have invented a new, original, and ornamental Design for a Wrench, of which the following is a specification, reference being had to the accompanying drawing, forming part thereof.

Figure 1 is a front elevational view of a wrench, showing my new design.

Figure 2 is a side view, and

Figure 3 is a bottom view.

I claim:

The ornamental design for a wrench, as shown.

ROY HUNTER DICKENSON.
